STERILIZER

James B. Pentz, Staten Island, N. Y.

Application June 28, 1948, Serial No. 35,553

1 Claim. (Cl. 21—95)

1 The invention is concerned with methods of sterilization by means of superheated steam and with apparatus connected therewith. More especially, it is concerned with the cover of such apparatus. The cover may be employed in combination with steam chests such as the ordinary type of sterilizer or the autoclave sterilizer where steam is held under pressure. It is also adapted to various types of cookers.

The main object of the invention is to reduce if not to eliminate the condensation of steam in a conventional steam chest when provided with a removable cover. As the cover extends over an air space which acts as an insulator between it and the portion usually referred to as the boiler, and as the cover is often open, condensation of the steam coming in contact with the cooler surface of the cover is unavoidable, resulting in defective asepsis because of the drippings from the cover. I have found that it is this failure of the heat in the cover to at least equal the heat of the walls of the steam chest which is responsible for this defective asepsis. I have also found that the defects are immediately corrected by "jacking up" the heat in the cover by means independent of the conventional boiling process. This novel attack of the problem not only allows surgical instruments placed in the steam chest to become thoroughly sterilized, but eliminates permeation of moisture and dripping of water into such articles as surgical dressings placed in the steam chest. What is no less important is that these results are obtained in so short a space of time that it well may be said that they are instantaneous.

In accordance with the above stated object, I provide the cover of my steam chest with a "hot plate," usually by means of an electric current passing through a resistance wire in the well known manner. The hot plate may be either on the inside or on the outside of the cover, but always in close contact therewith.

While my invention is herein illustrated mainly in its application to present day sterilizers, it will be understood that the novel features embodied in the cover will be equally efficient when the invention is applied to steam chests of other description, as, for instance, pressure cookers. It will be understood, further, that the steam chest may be of any suitable configuration, although here shown as cylindrical in form.

In present day practice, after the process of sterilization has been completed and the sterilized articles are about to be removed from the steam chest, the operator, upon removing the cover, finds the inside of the cover thoroughly

saturated with condensed steam which is apt to drip back into the sterilizer or fall to the floor of the room.

It also has been found that the surgical dressings, which usually are placed in a tray near the top of the sterilizer adjacent the inside of the cover, become contaminated by the condensations dripping from the cover, especially while the cover is being removed.

10 The present invention obviates all of the above difficulties by providing an electrical heating unit in close contact with the cover which keeps the entire sterilizer equally heated and does away with any cool portion where the steam may condense and drip back into the surgical dressings. Furthermore, in my process no air pockets are formed adjacent the cool cover which tend to delay or frustrate sterilization. It has been mentioned before that the heating unit may be underneath the cover or over it, but in all cases it must be in close contact with the cover. Other objects and advantages of the invention, not specifically mentioned above, will become apparent from the specification which follows and from the accompanying drawing, in which

Figure 1 is a vertical cross section of a sterilizer embodying the present invention, with the usual, standard valves and additional features and fixtures omitted for the sake of clarity.

30 Figure 2 is a modified form of the invention, also shown in vertical cross section.

Figure 3 is a similar cross section of a type of the invention provided with the preferred form of cover.

35 Figure 4 is a top plan view of the electrical element used for heating the various covers.

Figure 5 shows the present invention adapted to a deep well pressure cooker.

Referring to the drawing in detail, in Figure 1 there is shown in a diagrammatic way a conventional sterilizer comprising a chest 10 having a base portion 11 and a cover 12, with the usual heating element 13 in a chamber 14 at the base 11 of the chest 10. The chest 10 is provided with brackets 15 and 16 secured therein for supporting a pair of removable trays 17 and 18. These trays have openings 19 for the reception of hooks for placing them into and removing them out of the chest 10. The trays 17 are used for holding surgical instruments, and the trays 18 are for bandages and other surgical dressings to be sterilized. The cover 12, which may be hinged or bolted to the chest 10, contains a heating unit 13' in a chamber 21, formed by the shield 12'. The shield 12' may be provided with perforations along its upper surface to allow heat

to escape, or it may be omitted altogether. The shield 12' is removably secured to the cover 12 in any suitable manner by means omitted from the drawing. When the steam strikes the inner surface 40 of the cover 12, the cover is heated by the heating element 13', which prevents the condensation of steam on the surface 40, so that no water may drip onto the bandage tray 18 during sterilization and no water will drip to the floor when the cover 12 is removed from the chest 10 after sterilization.

The heating elements 13 and 13' are preferably circular in plan and cross section and are sheathed or covered with an insulating material 22. The terminals of the heating elements are adapted to be connected to a plug 23 which, in turn, is connected to the house current. When the shield 12' is omitted, the heating unit is exposed. It may be of any suitable form. In some cases, it may be provided by a flat iron.

The apparatus may be used both for sterilization with steam, in which case the water in the steam chest is heated by the electric element 13, or for dry heat sterilization, in which case the chest is emptied of the water, as by means of a petcock 41 shown in Figure 1. When sterilizing by steam, the level of the water is usually maintained above the tray 17 which holds the surgical instruments. When sterilization is done by dry heat, the surgical dressings are placed in the upper tray 18, the heat again being applied through the electrical element 13, but an absorbing pad 42, preferably of asbestos, is placed over the element 13. To prevent the burning out of the heat element, the absorbing pad 42 is kept moist by allowing water to drip onto it from the cup 24.

In the modified form of sterilizer shown in Figure 2, the tray 18 containing the surgical dressings may be dry heat sterilized in a separate container 25 having an exposed heating unit 26 connected to a plug 27. In this modification, it is immaterial whether the steam chest is emptied of water or not, in so far as sterilization of surgical dressings is concerned.

The container 25 is flared at the base to snugly fit over the shield 12' and may be removed by the bail 28. In this type of the invention, the circular brackets 29 may be interrupted so that the interrupted flange in the tray 18 may be inserted from the bottom of the container 25 and rotated for locking and removing.

Figure 5 shows a type adapted to a pressure cooker 30 which may or may not be of the deep well character. The cooker is shown seated in

an electric range 31 which has an independent electrical heating unit 32.

In the type illustrated in Figure 3, the cover comprises a dome 32 and a flange 33 which may or may not be bolted to the steam chest 10. It consists of metal plates 34 and 35 which are sealed together at the flanged portion 33 but separated at the dome portion to form a chamber 36 for accommodating a heating unit 13'. To prevent air pockets which often are formed during sterilization at or near the cover of the steam chest, the steam which enters the chamber 36 through the upper port 37 causes the heavier air to be driven out through the lower port 38, these ports being provided in the absorbing lining 39 and the metal plate 35.

Many variations in the structure of the device and in the character and disposition of its elements may be made by those skilled in the art without departing from the substance and spirit of the invention, the scope of which is covered by the claim which follows.

I claim:

25 In a steam chest for sterilizing surgical instruments and dressings, a removable top cover for said chest, spaced trays for respectively holding said instruments and dressings, said tray for said dressings being disposed above said other tray and adjacent said cover, and means in contact with said cover for heating said dressings independently of the steam in said chest.

JAMES B. PENTZ.
